UNITED STATES PATENT OFFICE.

LUPTON VANHAM, OF JAMESTOWN, NEW YORK, ASSIGNOR OF ONE-HALF TO
FREDERICK WILLIAM DIXON, OF JAMESTOWN, NEW YORK.

SPINNING-MACHINE.

1,160,017.

Specification of Letters Patent.

Patented Nov. 9, 1915.

Application filed September 9, 1914. Serial No. 860,836.

To all whom it may concern:

Be it known that I, LUPTON VANHAM, a subject of the King of Great Britain, and a resident of Jamestown, in the county of Chautauqua and State of New York, have invented new and useful Improvements in Spinning-Machines, of which the following is a full, clear, and exact description.

The object of the invention is to provide certain new and useful improvements in spinning machines, whereby the ordinary top board now generally used is dispensed with and accumulation of fly waste and loose fibers is prevented, to insure the formation of a thread free from fly or waste slubs, and whereby the spinner is enabled to quickly and conveniently make short piecing, and more room for doffing and setting of the bobbins is provided.

In order to accomplish the desired result use is made of individual swing arms, one for each thread, and a hinge connecting the rear end of each arm with the frame of the spinning machine, each arm being provided in its free end with a porcelain pot-eye for the passage of the thread.

A practical embodiment of the invention is represented in the accompanying drawings forming a part of this specification, in which similar characters of reference indicate corresponding parts in all the views.

Figure 1 is a plan view of the improvement as applied; Fig. 2 is an edge view of the same with a portion of the frame of the spinning machine shown in section; and Fig. 3 is an enlarged sectional elevation of the improvement on the line 3-3 of Fig. 2.

Arms A, one for each thread, are connected individually by hinges B with the frame C of the spinning machine, as plainly indicated in Figs. 1 and 2. The forward free end of each arm A is provided with a split seat A' in which is removably seated a porcelain pot-eye D of usual construction to form a guide for the corresponding thread. Each porcelain pot-eye D is provided with a split in register with the split of the seat A', and the upper end of each pot-eye D is provided with a flange D' seated on the seat A' to hold the pot-eye in place. The hinge B is constructed to normally hold the arm A in an approximately horizontal position during the spinning operation and when a bobbin is filled the arm A is swung upward into an approximately

vertical position for doffing or other purposes. The pot-eyes may be provided with various sized openings to accommodate different counts of spinning. Each pot-eye may be fastened in place by cement or other adhesive substance or it may be removably held in place in the seat A' by a plate F secured to the upper face of the corresponding arm A by a screw E or other means. The plate F is provided at its forward end with an eye F' overlying the flange D' so as to hold the pot-eye D securely in position on its seat A'. The eye F' is provided with a split in register with the splits of the seat A' and the pot-eye D, as will be readily understood by reference to Fig. 1. The rear end of the plate F extends beyond the screw E and is provided with a curved flange F² engaging the pivotal portion of the hinge B so as to bear on the same with a view to hold the arm A in raised position, as plainly indicated in dotted lines in Fig. 2. It is understood that when the spinning frame has been replenished with empty bobbins the operator can readily swing the arms A downwardly and forwardly back into active position.

It will be noticed that by the use of the plate F the pot-eye D is securely held in position on the arm A, and in case the pot-eye becomes injured or broken it is only necessary for the operator to loosen the screw E for convenient removal of the pot-eye D and to replace the same by a new one, after which the plate F is returned and fastened in place by the screw E. It will also be noticed that by the arrangement described the ordinary top board now generally used is entirely dispensed with and each individual arm can be swung into horizontal or vertical position at the option of the operator without moving the entire top board into the same position. It will further be noticed that the accumulation of fly waste or loose fibers is prevented, to insure the formation of a thread free from fly or waste slubs, and the spinner is enabled to quickly and correctly make a short piecing, and more room for doffing and setting of bobbins is provided.

Having thus described my invention, I claim as new and desire to secure by Letters Patent:

1. A spinning machine provided with a series of swing arms one for each thread, a

110

pot eye in the free outer end of each arm, a hinge connecting the rear end of each arm with the frame of the spinning machine, and a plate secured to the arm and bearing at 5 its rear end on the pivotal portion of the hinge.

2. A spinning machine provided with a series of swing arms, one for each thread, a hinge connecting the rear end of each swing 10 arm with the frame of the spinning machine, a pot eye in the forward end of the swing arm, and a plate secured to the arm between the ends thereof, one end of said plate bearing on the pot eye and the other 15 end frictionally engaging the pivotal portion of the hinge.

3. A spinning machine provided with a series of swing arms, one for each thread, a hinge connecting the rear end of each swing 20 arm with the frame of the spinning machine, a porcelain pot-eye in the free outer end of the swing arm, and a plate removably secured to the arm between the ends thereof, the forward end of the said plate having an 25 integral split eye overlying the rim of the said pot-eye, and the rear end of the said

plate having a curved flange frictionally engaging the hinge.

4. A spinning machine provided with a series of swing arms one for each thread, a hinge connecting the rear end of each swing arm with the frame of the spinning machine, the forward end of each arm being provided with a split seat, a porcelain pot-eye provided with a split in register with the split 35 of the seat, the upper end of the pot-eye being provided with a flange seated on the said seat, and a plate removably secured to each swing arm, and provided at its forward end with an eye overlying the flange of the 40 pot-eye and having a split registering with the splits of the seat and the pot-eye, the rear end of the plate extending over the pivotal portion of the hinge and bearing on the same. 45

In testimony whereof I have signed my name to this specification in the presence of two subscribing witnesses.

LUPTON VANHAM.
